UNITED STATES PATENT OFFICE

JAMES H. HOWARD, OF MEDFORD, MASSACHUSETTS.

SAFE.

SPECIFICATION forming part of Letters Patent No. 661,989, dated November 20, 1900.

Application filed December 9, 1897. Serial No. 661,232. (No model.)

To all whom it may concern:

Be it known that I, JAMES H. HOWARD, of Medford, in the county of Middlesex and State of Massachusetts, have invented certain new and useful Improvements in Safes, of which the following is a specification.

This invention relates to safes and vaults; and it consists in certain features of novelty in construction and arrangement which I shall now proceed to describe and claim, the particular object in view being to so construct the jamb and door of the safe or vault as to give greater security against the attacks of burglars than heretofore.

15 In the accompanying drawings, forming a part of this specification, Figure 1 represents a front view of one form of hinge used in my improved construction. Fig. 2 represents a front view of the safe with the door and hinge in place. Fig. 3 represents a horizontal section of the same. Figs. 4, 5, and 6 represent views similar to Figs. 1, 2, and 3, showing slight modifications in the construction of the door, hinge, and jamb.

25 The same reference characters indicate the same parts in all the figures.

Referring to the drawings, the letter *a* designates the door of a safe, and *b* *b'* the jamb. *d d* designate flat locking bolts or tongues 30 which are arranged to be projected from the jambs into the door-space and lock in a groove formed in the door *a*. The jamb departs in its construction from the usual construction of jambs in the following manner, as may be seen in Figs. 3 and 6: Instead of building up the jamb entirely of flat plates and angles whose terminal edges abut against the door, so that the crevices between the layers are brought out to the door-opening, which is the 35 present practice in safe-building, I build up the first few layers of the jamb by using angle-plates and *Z*-plates, as indicated in the said figures. In Fig. 3 the outside front layer of the jamb on the left of the door is a *Z*-plate

45 *b²*, which has a limb 2 extending parallel to the side of the door-opening. The next layer is an angle-plate *b³*, extending out flush with the limb 2 of the plate *b²*. The third layer is an angle-plate *b⁴*, which has a long limb 3 50 projecting outwardly in the same manner as the limb 2 of the outer plate and also extending over and covering the crevice between the

plates *b²* and *b³*. The fourth and fifth layers of the jamb extend out farther into the door-opening, so as to give the usual stepped construction to the jamb. The arrangement of the plates on the right-hand side of the door-opening is the same as that on the left, excepting that the limb 2 of the outer plate on the right is cut away even with the limb 3 of the third plate, so as to admit the hinge, whereas on the left the limb 2 extends beyond the limb 3 a distance equal to the thickness of the hinge. The door-abutting faces of the limbs 3 3 are slightly beveled, so as to admit the door easily, and the edges of the door-plates are correspondingly beveled, so as to make a snug fit against the jamb. It will be observed that the above construction of the jambs forms a sort of portico or vestibule into which the 60 door shuts. The edges of the jamb all around the door-opening are raised or protruded, so as to form a continuous tongue or flange.

In Figs. 1, 2, and 3 I show a crane-hinge for attaching the door to the safe-body, consisting of hinge-butts *c' c'*, affixed in a suitable manner to the door, and a main hinge-piece *c*, having one set of bearings *c² c²* on the jamb and another set *c³ c³* on the door at the hinge-butts *c' c'*. It will be noted that the 65 top bars or portions of the hinge-piece *c* extend over and protect the top and bottom horizontal portions of the crevice between the door and jamb, while the vertical connecting bars or portions of said hinge-piece cover and 70 protect the vertical portions of the crevice. The object of this construction is to protect this crevice from the immediate use of the wedge and similar tools and from the introduction of liquid or other explosives. Before such an attack can be made it is necessary to first remove the hinge.

By forming the jamb and door of a safe as hereinbefore described the use of a wedge to separate the door from the jamb by the ordinary method is prevented. If a wedge is interposed and driven downwardly between the layers of the jamb, the effect is to try to rend the parts of the jamb asunder instead of separating the door from the jamb, as would be 75 the case with the ordinary construction of jamb and door, wherein the crevices between the front layers of the jamb terminate in the door-opening.

Referring now to Figs. 4, 5, and 6, it will be noted that the construction is in the main similar to that described, with the following slight exceptions: The hinge is made in two parts or leaves c^4 and c^5 . The inner part c^5 fits close against the door and is so formed that it lies mainly within the vestibule formed by the projecting edges of the jamb. Its edges overlap the raised flange formed by the first two jamb-plates. The outer jamb-plate in this case has a limb 5, which covers the edge of the second plate and makes the crevice between the two plates abut against the hinge-piece c^5 when the door is closed. The hinge-piece c^4 is offset at 6 to pass around the right-hand portion of the raised flange and forms an additional protection at this point. The raised flange around the door-opening of the safe, in combination with the door located some distance back in the door-opening, as described, prevents the successful use of a "jimmy," since a fulcrum cannot be obtained on the jamb near the operating end of the tool as with a flush-door and jamb.

I claim—

1. In a safe or vault, the combination of a door, and a jamb built up of layers or plates of material, one of which plates within the

jamb has a portion next the door-opening extending outwardly across the ends of the front plate or plates and out to or beyond the front surface of the door, whereby an unseamed outer jamb is formed to the depth of two or more jamb-plates, for the purpose specified.

2. In a safe or vault, the combination of a door, a jamb built up of layers or plates of material, one or more of which plates have portions extending outwardly parallel to the door-opening and beyond the front surface of the jamb, so as to form a protruding flange around the door-opening, and a hinge having top and bottom horizontal portions and a vertical portion uniting said horizontal portions, the said vertical portion being offset to pass the flange, and extending over and protecting the vertical joint between the door and jamb on the hinge side of the door.

In testimony whereof I have signed my name to this specification, in the presence of two subscribing witnesses, this 3d day of December, A. D. 1897.

JAMES H. HOWARD.
